(57) **CLAIM**

We claim the ornamental design for an architectural panel with broom blooms embossed surface, as shown and described.

DESCRIPTIONFIG. 1 is a perspective view of an architectural panel with broom blooms embossed surface, showing our new design
FIG. 2 is a front view of the architectural panel with broom blooms embossed surface.

FIG. 3 is a back view of the architectural panel with broom blooms embossed surface.

FIG. 4 is a left side view of the architectural panel with broom blooms embossed surface.

FIG. 5 is a right side view of the architectural panel with broom blooms embossed surface.

FIG. 6 is a top view of the architectural panel with broom blooms embossed surface; and,

FIG. 7 is a bottom view of the architectural panel with broom blooms embossed surface.

The broken lines adjacent to the shaded portions of the design depict the bounds of the claim and all other broken lines depict environmental subject matter. All broken lines form no part of the claim.
